ALPHONSE GABRIEL, OF OAKLAND, CALIFORNIA

COIN-CONTROLLED LOCK

Application filed June 11, 1926. Serial No. 115,223.

My invention relates to a door-lock which is arranged to be rendered operable by and upon the deposit of a coin, or the like, therein, and particularly to locks in which the coin itself is utilized in providing direct operative connection between the latch bolt and the latch operating means.

An object of the invention is to provide a lock of the class described having means arranged to prevent the insertion of a second coin while a first coin is operatively disposed in the lock.

Another object of the invention is to provide a coin-controlled lock with means permitting the operative insertion of a coin therein only when the various operative parts are in a particular position.

A further object of the invention is to provide a lock of the class described in which the operative parts may assume their particular coin receiving relation without regard to the positioning of the latch bolt with respect thereto.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a side sectional view of a lock embodying my invention.

Figure 2 is a side view of the lock, portions thereof being broken away to disclose certain parts disposed in different operative relation than in Figure 1.

Figure 3 is a sectional view taken on the line 3—3 in Figure 1, the mounting of the lock on a door also being shown.

Figure 4 is an edge view of the lock installed on a door.

Figure 5 is a sectional view taken on the line 5—5 in Figure 1.

Figure 6 is a sectional view taken on the line 6—6 in Figure 1.

As illustrated in the drawings, the lock 7 of my invention comprises a latch plate 8 carrying a latch bolt 9, and means independently operable from different sides of the door for actuating the latch-plate to withdraw the bolt, one of said means being coin-controlled. The lock mechanism, it will be noted, is here shown mounted on a plate 11 arranged to be secured directly to a door 12, which plate conveniently serves as part of the lock housing. Movement of the latch-plate is here shown arranged to be accomplished from the outer side of the door upon the appropriate manipulation of a spindle 13 which carries a member 14 having an arm 16 extending radially therefrom, which latter is directly utilized in effecting the movement of the latch plate.

The latch-plate 8, it will now be noted, is mounted for reciprocation above the spindle 13 in suitable guideways provided in the plate 11 and a plate 17, which latter plate is arranged to be held in fixed opposed relation to the plate 11 by means of cooperating spacing posts 18 and screw bolts 19. Furthermore, the latch plate is vertically slotted at its inner end to provide a space 21 in which the arm 16 is arranged to be normally permitted to freely oscillate without effecting any movement of the latch-plate. The latch-plate portions 22 which provide the side walls of the space 21 are provided with opposed vertically disposed slots 23 of such depth that together they define a guideway for a coin of the denomination to be used in the lock. When, as here shown, a coin 24 is disposed in the slots 23, it will be obvious that the rotation of the arm 16 from a position forwardly of the coin will cause it to engage the latter, and that further rotation of the arm will cause the retractive movement of the latch-plate through the engagement of opposite portions of the coin against the rearward edges of slots 23. In this manner, the coin itself is actually utilized as an operative part of the lock, since without it the retraction of the latch-plate by means of arm 16 is impossible. Then arm 16, it will be noted,

is 80
85
90
95
100

is arranged to be normally held positioned forwardly of the coin slots 23 by means of a suitable spring 27 operatively connecting the member 14 to a point on the plate 11 forwardly of said member, the forward movement of the arm being limited by its contact with the forward wall 28 defining the space 21, so that the arm 16 will thus normally lie in fixed relation to the latch-plate.

10 Means are provided for holding the coin in proper operative position in the slots 23, during the oscillation of the arm, and, as here shown, such means comprise the provision of a shoulder or seat 29 at the base of the arm 16 so disposed that the lower edge of the coin will rest and be held thereon when the coin is properly positioned in the slots. In this manner, movement of the arm toward the coin will not dislodge the latter and operation of the latch in the manner specified is assured.

Since in locks of the class described it is usually desirable that the use of a different coin be required each time the door is opened, 25 means are provided for releasing the coin from its position in the slots to permit the deposit of another coin in the lock. As here shown, such means comprise the provision of a second spindle 31 having a radial arm 32 extending therefrom to engage the rearward wall 33 of the space 21 and operable from the inside of the door to retract the latch-plate independently of the arm 16. The slots 23, it will now be noted, are somewhat wider 35 than the thickness of the coin and the seat 29 slopes rearwardly and downwardly, so that when the arm 32 retracts the latch-plate to take up the lost motion provided, the coin will slide downwardly from its seat and out 40 of the slots. In this manner, the placing of a coin in the lock mechanism will allow the retraction of the bolt by the operation of the spindle 13 from the outside of the door, while the operation of the spindle 31 to cause the 45 retraction of the latch-plate will not only open the door but will simultaneously release any coin which may be operatively disposed in the latch-plate.

Means are provided for guiding a coin to 50 its proper position in the slots 23 when the latch-plate is in its forward position. As here shown, such means comprises the provision of members 34 formed integral with the plate 11 and extending outwardly therefrom above the latch-plate, such members defining a guideway 36 between them which is aligned with the slots 23 when the latter are in normal position, the lower edge of such guideway being adjacent the latch-plate. 55 Pivottally mounted on the rearmost member 34 for free movement about a horizontal axis is a member 37 so shaped and mounted that the lower end 38 thereof normally projects into the plane of slots 23 and guideway 36, 60 while the upper portion 39 lies outside of said

plane. When, however, a coin is positioned in the slots, the pivotal displacement of the lower end of member 37 by the coin is arranged to cause the upper end 39 to move across an end of the guideway 36 and so prevent the insertion of a second coin therein. By providing on the arm 16 a pin 42 which extends into the plane of movement of the member 37, the latter may be caused to move to close the guideway 36 to a coin upon displacement of the arm 16 upon rotation of the spindle.

Means are also provided for barring the insertion of a coin or other object through the guideway 36 and behind the arm 16 when the latter is positioned rearwardly of the plane of the guideway as by the turning of the spindle with or without a coin operatively disposed in the lock. As here shown, such means comprises a projection 43 extending tangentially forwardly from the end of the arm and arranged to extend across and under the lower end of the guideway 36 when the arm is in the position stated. In this manner, in the event that the spindle 13 is rotated prior to the insertion of a coin in the guideway, the deliberate or accidental holding of the latch-plate in withdrawn position by the insertion of such coin or other foreign object through the guideway is positively prevented, it being noted that the projection 43 is preferably so positioned and of such width as to completely cover the arm 16. In this manner, a coin or other object inserted while the arm 16 lies directly below or back of the guideway 36 will merely ride on the top of the projection 43 and so will be kept out of the operative mechanism.

A casing 44 for the structure hereinbefore described is provided, said casing being here shown of one-piece structure and having edge and front plate portions 46 and 47 respectively which cooperate with the back plate 11 to provide a complete closure for the lock mechanism. As here shown, the casing front 47 is provided with a door 49 arranged to be locked shut, and is secured to the plate 11 by means of screw bolts 50 whose heads are preferably exposed only upon removal of the door 49. In this manner, a coin box is provided below the lock mechanism and the mounting and dismounting of the lock is possible only when the door 49 is open. A slot 51 at the top of the casing is provided to permit the dropping of a coin in the guideway 36, while the latch bolt is arranged to be reciprocated through an edge perforation 52. It will be noted that this structure permits the unitary assembly of the lock mechanism on the plate 11 independently of the casing 44.

The latch bolt 9, it will now be noted, is here shown mounted in a cavity 53 provided in the outer end of the latch plate and is slidably engaged in such cavity, being urged

to maintain an outward position therein by reason of a spring 54 engaged between it and the inner end of the cavity. In this manner, prying back of the latch bolt does not effect 5 the movement of the latch plate, while preventing the complete outward movement of the bolt does not interfere with the normally aligned positioning of the guideway 36 and slots 23. To permit the use of the lock for 10 either inward or outward swinging doors, the bolt is preferably reversible in its socket, and is adapted to be held therein by means of a stop pin 56 which is arranged to be reciprocated in a slot 57 and to be set in either 15 side of the bolt, it being noted that reversal of the bolt is thus made possible without involving the dismounting of the lock.

As here shown the spindle 13 is operable by means of a knob 58 fixed thereto at the 20 front of the door, while the spindle 31 is arranged to be operated from the inside of the door by a knob 59, so that dropping of the coin is thus insured upon the opening of the door to effect an exit. If desired, the operation 25 of the spindle 31 may also be effected from the outside of the door by the use of a suitable key, the casing being here shown provided with a suitable keyway 61 for the purpose.

30 To further insure the normally forward positioning of the latch plate, and to hold the coin and arm 16 in contact during operative oscillation of the arm, a compression spring 61 is preferably interposed between the inner end of the latch plate and the adjacent casing side 46, while undue backward movement of the arm 16 is here shown prevented by providing the member 14 with a second arm 62 which is arranged to engage a post 40 18 when the arm 16 lies at its desired backward position.

Further protection against tampering is here shown provided by forming the casing with a guard flange 63 which extends beyond 45 the protruding portion of the latch bolt on three sides thereof. Furthermore, a reinforcing plate 64 is preferably secured to the plate 11 adjacent the opening 52, such plate being here shown arranged to define the rearward 50 side of the cavity 53 and providing at its inner end the necessary stop by which the outward movement of the latch plate is limited.

It will be noted that, as herein particularly 55 shown and described, positioning the axis of the spindle 13 in the plane of the coin slots 23, making the parts reversible, and providing for a suitable change of mounting, have provided a lock adapted for mounting either 60 on right or left hand doors without involving any alteration of the parts of the operative mechanism thereof.

It will now be obvious that a lock has been 55 provided which is particularly valuable for use in the doors of pay toilets or the like, and

that, with the coin used as part of the operating mechanism, provision has been made to insure its positive functioning at all times. And it will be further noted that particularly effective means are provided for preventing tampering with the lock by unauthorized persons or the insertion of a coin in the operative mechanism thereof, when such insertion will not render the lock operative.

I claim:

1. In a door lock, a vertically perforated latch plate having spaced side walls provided with upstanding slots to receive a coin and to hold the same with its face at substantially a right angle to the direction of travel of the latch plate, resilient means to project the latch plate, an arm pivotally supported beneath the latch plate and having its free end projecting into the perforation and arranged between the side walls to engage the face of the coin, and a shoulder carried by the arm and arranged to engage the lower edge of the coin to support the same.

2. In a coin-controlled lock mechanism, a movable bolt, means operative to displace 90 said bolt, bolt operating means independent of said first means and normally inoperative to displace said bolt, means utilizing a coin to operatively connect said second means with said bolt, means normally operative to 95 retain a coin operatively disposed in the mechanism following a displacement of the bolt through the actuation of said second bolt operating means, means operable upon operative actuation of said first bolt displacing 100 means to release the coin from the mechanism, and a pivoted guard member arranged to be engaged, moved and maintained in position to prevent the insertion of a coin into the mechanism, by a coin held by said retaining means, and means carried by the second bolt operating means for engaging and moving the guard member into operative position when the said second means is operated without a coin in the mechanism.

3. In a door lock a vertically perforated latch plate having slots on opposite sides of the perforation for the passage of coin through said perforation, means resiliently urging the latch plate to maintain a normally projected position, a pivotally mounted arm arranged to be moved in said perforation into engagement with a coin held in said slots, a shoulder on said arm releasably supporting the coin in said slots, and a guard member 115 arranged to be engaged by the coin held in said slots and to be held by such engagement in position to prevent the insertion of a coin into the mechanism.

4. In a door lock a vertically perforated 125 latch plate having slots on opposite sides of the perforation for the passage of coin through said perforation, means resiliently urging the latch plate to maintain a normally projected position, a pivotally mounted arm 130

arranged to be moved in said perforation into engagement with a coin held in said slots, a shoulder on said arm releasably supporting the coin in said slots, a guard member arranged to be engaged by the coin held in said slots and to be held by such engagement in position to prevent the insertion of a coin into the mechanism, and a member on said arm arranged to engage and move the guard into operative position when the arm is moved in said perforation while no coin is held in said slots, and being inoperative when a coin is present in said slots.

In testimony whereof, I have hereunto set
15 my hand this 5th day of June, 1926.

ALPHONSE GABRIEL.
